(57) **CLAIM**

The ornamental design for a hat with an opening and pocket for accommodating a cochlear implant, as shown and described.

DESCRIPTION

FIG. 1 is a front perspective view of a new design for a hat with an opening and pocket for accommodating a cochlear implant.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view thereof, as it may appear when in use.

The broken line outline of the partial human figure and cochlear implant in the view of FIG. 8 assist in illustrating how the claimed design may appear when worn, but forms no part of the claimed design.
